COMBINED CONDIMENT JARS OR THE LIKE AND STAND THEREFOR

Clara Virginia Eicholtz, Midland, Mich., assignor to The Dow Chemical Company, Midland, Mich., a corporation of Delaware

Filed Dec. 10, 1962, Ser. No. 72,781

Term of patent 14 years

(Cl. D44—22)

FIGURE 1 is a side elevational view of combined condiment jars or the like and stand therefor, showing my new design;

I claim:

The ornamental design for combined condiment jars or the like and stand therefor, as shown.
